INK AGITATOR DEVICE

Harold W. Gegenheimer, Darien, Conn., and William Gatto, Brooklyn, and Andrew N. Stad, Syosset, N.Y., assignors to Baldwin-Gegenheimer Corporation, Brooklyn, N.Y., a corporation of New York
Filed Apr. 5, 1961, Ser. No. 100,956
11 Claims. (Cl. 101—364)

The present invention relates to agitators for printing press ink reservoirs or fountains and more particularly to improved mechanism for maintaining the ink in the reservoir in a continuously agitated or mixed condition for proper, uniform feeding onto the ink fountain roller.

Heretofore, ink fountain agitators for maintaining the ink in the reservoir in a mixed condition have only been generally available for printing presses having a substantial width; namely, at least twenty inches. This width limitation was dictated by the complexity of the agitator mechanism. However, there has developed a substantial demand for ink agitators capable of installation on smaller presses. This demand has been created in large measure by the increase in electronic bank check processing wherein checks are imprinted with a code number of magnetic ink. This code number produces a particular electrical signal when electronically processed, the signal so produced actuating electro-responsive check sorting and posting devices.

Magnetic ink encoding of checks is frequently carried out on presses fourteen inches in width for which no agitators were heretofore readily available. However, magnetic inks for check encoding contain ferrous particles which have a tendency to settle out of the ink solution and therefore must be continually agitated in the ink fountain to ensure proper decoding of the printed characters on the check. Further, many types of ink, especially the magnetic inks used in check encoding, exhibit a tendency to "back away" from the rotating fountain roller and must be continuously urged or force-fed into uniform contact with the fountain roller to avoid erratic application of ink to the ink fountain roller. Improper or non-uniform coverage of the ink fountain roller results in variations in the ink film thickness on the check, thereby producing a poor or incorrect signal during subsequent electronic processing of the imprinted check.

General Description

Accordingly, the present invention is characterized by the provision of an improved ink agitator unit which is compact, efficient and inexpensive and adapted for use with smaller printing presses than heretofore possible. The improved agitator unit comprises a rotatable conical agitator mill mounted for reciprocating travel in the ink reservoir or fountain. The unit includes a support-head member in which the mill is freely rotatably mounted. The support head member is driven back and forth in an elongated, enclosed housing supported above and parallel to the reservoir by an endless conveyor. A simplified device is provided for effecting reversal of the head drive. In the preferred embodiment, this device includes a transverse track formed in the head in which is slidably mounted a block connected to a drive pin on the conveyor. As the drive pin reverses direction with the endless conveyor, the track accommodates transverse travel of the block and pin, adapting the head for travel from one longitudinal direction in the housing to movement in the opposite direction. In a modified form of the invention, cam means effects reversal of movement of the head in the housing. In addition, a pinion fixed to the mill shaft is in meshing engagement with a vertically disposed rack member supported by the track. Reciprocal movement

2

of the head thus also effects simultaneous rotational movement of the mill.

To maintain the agitator unit in operative position in the ink fountain, the unit includes a pair of spaced clamp arms adapted to engage a portion of the press frame to fix the agitator unit in operative position, means is also provided for facilitating cleaning or replacement of the agitator mill. This includes a spring lock coupling for detachably connecting the mill to its operating shaft.

In a modified form of the invention, means is also included for varying the distance that the agitator reciprocates in the ink fountain. A pair of opposed cams are mounted on the cross head element and are adapted to be alternately engaged by the endless conveyor and driven back and forth. Camming elements adjustably mounted on each end of the elongated cross head track are operative to urge a particular cam into engagement with the endless conveyor while moving the other cam out of engagement therewith. Thus the camming elements effect reversal of the cross head at the end of run in the elongated track. Since the cam tracks are adjustably mounted, their relative spaced position can be selectively varied, thereby changing the distance the agitator unit travels in the ink fountain.

Objects

It is, therefore, an object of the present invention to provide an improved ink agitator unit that is compact, efficient and inexpensive, and adapted for use with small printing presses than heretofore possible.

It is another object of the invention to provide an improved agitating unit for use with printing presses employing magnetic inks wherein the unit includes a rotatable agitator mill mounted for reciprocating travel in the ink reservoir by means of a chain-driven cross head member.

Another object of the present invention is to provide an improved ink agitator unit having a rotatable agitator mill, and a spring lock coupling between the mill member and its operating shaft to facilitate removal of the mill for cleaning or replacement.

A further object of the invention is to provide an improved ink fountain agitator unit having an enclosed elongated housing disposed parallel to and spaced from the ink fountain roller which supports a head member for longitudinal reciprocating travel therethrough, and an agitator mill disposed in the fountain and connected to an operating shaft rotatably mounted in the head and including a chain conveyor in the housing for travelling the head back and forth therein while a rack and pinion arrangement in the housing simultaneously rotates the agitator shaft and mill.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate embodiments of the invention, and together with the description, serve to explain the principles of the invention.

In the drawings wherein like reference characters are used throughout to designate like elements:

FIGURE 1 is a plan view, partly in section, of the preferred embodiment of the present invention;

FIGURE 2 is a front view, taken along line 2—2 of FIGURE 1;

FIGURE 3 is a detailed sectional view, taken along line 3—3 of FIGURE 1;

FIGURE 4 is a sectional side elevation, taken along line 4—4 of FIGURE 1;

FIGURE 5 is a plan view, partly in section, of a modified form of the present invention;

FIGURE 6 is a sectional side elevation, taken along lines 6—6 of FIGURE 5;

FIGURE 7 is a bottom view of the mechanism illustrated in FIGURE 5;

FIGURE 8 is a detailed sectional view of the agitator mill coupling means;

FIGURE 9 is a side elevation illustrating the agitator unit in operative ink mixing and feeding position.

Referring specifically to FIGS. 1—4 of the drawings, there is illustrated the preferred embodiment of the invention which comprises a rotatable ink agitator unit, designed generally 10, which is mounted for travel back and forth in the ink fountain 12 of a conventional printing press (not shown). Unit 10 is supported for reciprocal travel in an elongated housing 14 of generally rectangular cross section. Housing 14 is supported at each end by a support bracket 16 pivotally connected at the upper ends thereof to a pin 19 extending from an associated end plate 18 of housing 14. The upper ends of brackets 16 are preferably bifurcated to accommodate pins 19. Cap screws 20 are provided for clamping the split upper ends of brackets 16 together, locking bracket 16 to pin 19 and thus to its associated end plate 18, positively securing housing 14 to its support brackets 16. Loosening of cap screws 20 permits housing 14 to be rotated relative to its support brackets 16 to any desired rotative position.

In operative position, housing 14 is generally spaced from and parallel to the ink fountain roller 11. The configuration of the brackets 16 is dependent upon the make or type of press on which the agitator unit 10 is to be mounted. In the typical installation illustrated, each bracket 16 extends transversely from housing 14 and includes at its free end, an arcuate front section 22 adapted to bear on the fountain roller support shaft 13. Brackets 16 also include a transverse rear section 24 having a notch or recess 26 formed therein. Notches 26 are adapted to receive a portion 28 of the press frame (not shown). Each section 24 is provided at its terminal end with a hub 30 which threadedly accommodates a lock screw 32 for travel into clamping engagement with the portion 28 of the press frame in notch 26 of its associated bracket 16. Thus, lock screw 32 clamps brackets 16 and housing 14 in position on the press frame as shown in FIG. 4.

The ink in fountain 12 is mixed or agitated for proper feeding to ink roller 11 by conical mixer element 34 located above the bed 36 of the fountain. Mixer element 34 is continuously reciprocated throughout the length of fountain 12 while being simultaneously rotated therein. Mixer element 34 is fixed to one end of a shaft 38. Shaft 38 is detachably connected by spring-lock coupling 39 to one end of drive shaft 40. The other end of shaft 40 is rotatably mounted in a support head member 42 which in turn is slidably supported in housing 14.

Head 42 is mounted between spaced front and rear plates 44 and 46 of housing 14 and adapted to travel longitudinal in housing 14. Front plate 44 has a transverse section 45 forming the top or cover of housing 14 to completely enclose head 42 on three sides. To travel head 42 along inside housing 14, there is provided a chain drive mechanism which includes endless chain conveyor 48 trained at one end about a sprocket 50 driven by suitable power source such as motor 52 and speed reducer 54 (see FIG. 1). Motor 52 is mounted on bracket 56 fixed on one end plate 18. Bracket 56 is slotted as at 57 for ease of assembly and to permit adjustment of motor 52 thereon accommodating any stretch

of chain 48. The other end of chain 48 is trained around an idler sprocket 58 rotatably mounted inside housing 14 to the underside of cover section 45. For reasons set forth hereinbelow, sprocket 58 is spaced from the other end plate 18.

As shown best in FIGS. 1 and 2, sprockets 50 and 58 mount chain conveyor 48 for travel in a plane generally parallel to cover section 45 and transverse to shaft 40 with the stretches of chain 48 adjacent front and rear plates 44 and 46 (see FIG. 3).

Chain conveyor 48 is connected in driving engagement with head 42 by means of pin 60 fixed to chain 48 which is freely accommodated in a block 62 slidably mounted in a transverse slot 64 formed at one side in the top face 43 of head 42. As chain 48 is driven around sprockets 50 and 58, pin 60 urges block 62 and thus head 42 in a direction parallel to the longitudinal axis of housing 14, travelling head 42 back and forth in housing 14. To support longitudinal movement of head 42, front plate 44 is provided with an elongated track or key 74 adapted to accommodate a cooperating keyway 76 in head 42 for supporting head 42 for longitudinal travel in housing 14.

With head 42 moving in the direction of arrow A, FIGS. 1 and 2, pin 60 travels in the chain stretch adjacent front plate 44 and block 62 is positioned in slot 64 adjacent the inner face of plate 44. With head 42 travelling in the direction of arrow B, FIGS. 1 and 2, pin 60 is traveled in the chain stretch adjacent rear plate 46 and block 62 has been moved by pin 60 into position adjacent the inner face of plate 46. As pin 60 moves from one stretch to the other around sprockets 50 and 58, block 62 is slid in slot 62 from one side of head 42 to the other. As stated above, sprocket 58 is spaced from its adjacent end plate 18. This is to accommodate the maximum limit of travel of head 42 in housing 14 in the direction of arrow A. FIG. 1 illustrates the maximum travel of head 42 in the direction of arrow B. However, when pin 60 passes around sprocket 58, because of the position of slot 64 therein, head 42 extends beyond chain 48 as shown in phantom in FIG. 1. By suitably spacing sprocket 58 from its adjacent end plate 18, accommodation is made for the maximum travel of head 42 in the direction of arrow A.

To rotate conical mixer element 34 simultaneously with the longitudinal travel thereof with head 42, mixer element drive shaft 40 is rotatably supported in spaced bearing rings 66 and 68 located in a central cavity 69 in head 42. Between spaced bearing rings 66 and 68, shaft 40 is provided in cavity 69 with a pinion 70 fixed to shaft 40 and rotatable therewith. To rotate pinion 70 and shaft 40, rear plate 46 supports an elongated rack section 72. Cavity 69 provides access to rack 72 for pinion 70 adjacent rear plate 46 and rack 72 is mounted in meshing engagement with pinion 70.

The teeth 71 of rack 72 are preferably disposed downwardly when located in operative position (see FIG. 3). This arrangement of teeth 71 precludes the possibility of any ink from fountain 12 dropping into rack 72 and thereby disrupting proper operation thereof.

Normally when head 42 is moving in the direction of arrow A, FIG. 2, mill 34 would rotate in a clockwise direction as viewed in FIG. 2 because of the functional contact with bed 36. However, it has been found that this normal rotation of mill 34 tends to cause accumulation or build-up of ink at the ends of fountain 12 resulting in improper ink feed by mill 34. Accordingly, the teeth 71 of rack 72 and pinion 70 are so constructed and arranged in meshing engagement that, when head 42 moves in the direction of arrow A, FIG. 2, mill 34 is rotated in a counter clockwise direction as viewed in FIG. 2. Likewise when head 42 moves in the direction of arrow B, FIG. 2, mill 34 is rotated by pinion 70 and track 72 in a clockwise direction as viewed in FIG. 2. Rotation of mill 34 in a direction opposite to that in which

it would normally rotate overcomes the problem of ink build-up.

As head 42 is reciprocated in housing 14 as described hereinabove, pinion 70 travelling therewith is rotated by the teeth 71 of rack 72 in one direction as head 42 moves in the direction of arrow A, FIG. 1. Upon movement of head 42 in direction of arrow B, FIG. 1, the rotation of pinion 70 is reversed. However, while the direction of rotation of pinion 70 and hence mixer 34 is alternated, the rotation thereof is continuous during the reciprocating travel of head 42.

When it is necessary to clean or replace mixer element 34, as when a new color ink is to be used, there is provided the spring lock coupling 39 which permits rapid removal of mixer 34 from its drive shaft 40. Referring specifically to FIG. 8, coupling 39 comprises a socket element 78 slidably mounted on the free end of shaft 38. Socket 78 has a cup-shaped cavity 80 formed therein to accommodate the stepped free end 41 of shaft 40. To couple shafts 38 and 40 adjacent the end 41 of shaft 40, there is provided a transverse pin 82, which is received in slot 84 formed in socket 78. Slot 84 is generally U-shaped and includes an entry section 86 which extends axially of socket 78 through the top thereof, a horizontal section 88 which accommodates pin 82 during relative rotation of socket 78 and pin 82. After entry into slot 84 at end of its travel in entry section 86 pin 82 is travelled through transverse section 88 by relative rotation of pin 82 and socket 78 to locking section 90. Locking section 90 is parallel to entry section 86 but terminates short of the top of socket 78. A compression spring 92 located in the bottom of socket 78 bears against a stepped cap 37 on the end of shaft 38. Cap 37 and end 41 of shaft 40 are provided with matching steps and spring 92 is operative to normally urge cap 37 and end 41 together, maintaining pin 82 in section 90 in locked position shown in FIG. 8. Sections 86, 88 and 90 are interconnected to form a continuous passage for the movement of pin 82 into and out of operative locked position.

To disconnect shafts 38 and 40, socket 78 is slid axially along shaft 38 against the action of spring 92, moving pin 82 through section 90 into alignment with section 88. Relative rotation between socket 78 and shaft 40 travels pin 82 through section 88 into alignment with section 84. In this position, the shafts 38 and 40 may be freely disconnected to permit replacement or cleaning of mixer 34. Socket 78 includes an annular knurled flange 94 formed on the outer periphery thereof to facilitate coupling and uncoupling of shafts 38 and 40. A snap ring 96 on the outer periphery of shaft 38, limits the axial travel socket 78 along shaft 38. Ring 96 and spring 92 thus maintain socket 78 and shaft 38 in operative pin receiving position when shafts 38 and 40 are uncoupled.

FIGS. 5-7 disclose a modified form of the present invention wherein means is provided for adjusting the length of reciprocal travel of the agitator unit. Like reference numerals indicate elements of similar construction and operation to elements in the preferred embodiment of the invention. In this embodiment, agitator unit 110 includes a head 142 adapted for reciprocal travel in housing 14 and driven by pin 60 on endless chain conveyor 48 as in the preferred embodiment. To connect head 142 in driving engagement with chain 48, head 142 is provided with a pair of spaced cam elements 144 and 145, each pivotally connected by an associated pin 145 to a side of head 142. Each cam 144 and 145 has an upper transverse section 148, 149 respectively adapted to be alternately positioned in the path of travel of pin 60 on chain 48. In addition, each cam 144 and 145 has a lower section 151, 153 respectively below their associated pin connection 145. Section 151, 153 extend outwardly from housing 14 for reasons set forth hereinbelow.

When travelling in the stretch of chain 48 adjacent rear housing plate 46, pin 60 is in engagement with sec-

tion 148 of cam 144 moving head 142 in the direction of arrow C, FIG. 5. When travelling in the chain stretch adjacent front plate 44, pin 60 is in engagement with section 149 of cam 146 urging head 142 in the direction of arrow D, FIG. 5.

To pivot cams 144 and 146 into and out of pin engaging position, there is provided elongated camming elements 150 and 152 adjacent each end of housing 14 which extend in directions parallel to the longitudinal axis of the housing. Camming elements 150 and 152 are mounted beneath housing 14 on opposite sides thereof. Camming element 150 is transversely supported in channel bracket 154 clamped, or otherwise detachably connected as by set screw 158, to the outer face of front housing plate 44. Camming element 152, in turn, is transversely supported in channel bracket 156 clamped or otherwise detachably connected as by set screw 158 to the outer face of rear housing plate 46. Each bracket 154 and 156 is formed with a lip section 161 which rests on rack 72 or track 74 respectively inside housing 14, thereby assisting in supporting its associated bracket 154 or 156 in position thereon.

Cam face 155 of camming element 150 is operative to engage lower sections 151 and 153 of both cams 144 and 146, pivoting section 148 of cam 144 out of the path of travel of pin 60 while concomitantly pivoting section 149 of cam 146 into the pin path at the limit of travel of head 142 in the direction of arrow C, FIG. 5. In like manner, cam face 157 of camming element 152 is operative to pivot cam 146 out of the path of travel of pin 60 while simultaneously moving cam 144 into the pin path at limit of travel of head 142 in the direction of arrow D, FIG. 5. A spring detent 159 is provided for each cam 144 and 146. Detents 159 apply a slight outward pressure against their associated cams 144 and 146, maintaining cams 144 or 146 in the various pivoted positions they assume through the action of camming elements 150 or 152.

It will be understood that upon disengagement of pin 60 and cam 144 through the action of camming element 150, the travel of head 142 is momentarily interrupted until the chain link carrying pin 60 is travelled from the stretch adjacent rear plate 46 into the stretch adjacent front plate 44 around sprocket 50. Head 142 is also temporarily halted when cam 146 and pin 60 are disengaged by camming element 152 adjacent the other end of housing 14.

When it is desired, the distance of reciprocal travel of head 142 can be selectively adjusted by varying the location of brackets 154 and 156 and their associated camming elements 150 and 152, respectively. Set screws 158 can be loosened and the position of either or both brackets 154 and 156 changed on housing 14. Re-tightening of screws 158 changes its associated bracket 154 and 156 in this new location.

Head 142 is supported for reciprocal travel by a keyway 160 formed therein adapted to accommodate track or key 74 on front plate 44. Further head 142 includes an internal cavity 141 to accommodate pinion 70 on shaft 40 which is supported and rotated as hereinbefore described in connection with the preferred embodiment of the invention. Further, because of the manner in which head 142 is driven by chain conveyor 48, sprocket 58 can be located adjacent its associated end plate 18 without adverse effect.

Thus there is disclosed a simple, efficient, inexpensive and highly reliable ink agitator unit especially adapted for smaller presses and for use with magnetic inks.

The invention, in its broader aspects, is not limited to the specific mechanism shown and described but departures can be made therefrom within the scope of the accompanying claims, without departing from the principles of the invention and without sacrificing its chief advantages.

What we claim is:

1. An agitator device for the ink fountain of a printing press comprising in combination an elongated housing enclosing said device, a support bracket at each end of said housing for mounting said housing in spaced parallel disposition to the ink fountain roller of said press, means for clamping said brackets to the frame of said press, means rotatably securing said housing to said brackets for varying the rotational disposition of said housing relative to said roller, an agitator mill depending from an open section in said housing and disposed in said fountain, a shaft operatively associated at one end with said mill for rotating said mill and travelling said mill longitudinally in said fountain, a mill support head slidably supported in said housing, means rotatably supporting the other end of said shaft in said support head, an endless conveyor, means mounting said conveyor in said housing, means for travelling said conveyor in said housing, means operatively associating said conveyor with said head for travelling said head longitudinally back and forth through said housing, and means in said housing for effecting rotation of said mill shaft simultaneously with the movement of said head by said conveyor.

2. The invention as defined in claim 1 where said mill is conical and detachably coupled to its associated shaft and wherein said shaft rotating means includes a pinion fastened to said shaft and a rack secured to said housing and in meshing engagement with said pinion for effecting rotation of said pinion and associated shaft in response to longitudinal movement of said head and housing.

3. The invention as defined in claim 1 wherein said conveyor comprises an endless chain mounted for travel in said housing in a plane generally transverse to said mill shaft.

4. The invention as defined in claim 2 including a track in said housing and an accommodating keyway formed in said head, said track and keyway slidably supporting said support head in said housing.

5. The invention as defined in claim 2 wherein the teeth of said rack are disposed downwardly when said housing is in operative position on said press whereby the deposit of ink thereon is prevented to ensure clog-free operation thereof.

6. An agitator device for the ink fountain of a printing press comprising in combination an elongated housing, a support bracket at each end of said housing for mounting said housing in spaced parallel disposition to the ink fountain roller of said press, means for clamping said brackets to the frame of said press, means rotatably securing said housing to said brackets for varying the rotational disposition of said housing relative to said roller, a conical agitator mill for said fountain, an operating shaft for said mill, means detachably coupling said mill to one end of said operating shaft, a mill support head slidably supported in said housing, means rotatably supporting the other end of said shaft in said support head, an endless chain conveyor, a sprocket at each end of said housing mounting said chain conveyor for travel therein in a plane generally transverse to said mill shaft, means for rotating one of said sprockets for travelling said conveyor through said housing, a drive pin on said conveyor, means operatively associating said drive pin with said head for travelling said head longitudinally back and forth through said housing, a pinion fixed to the portion of said mill shaft in said support head, and a rack secured to said housing and in meshing engagement with said pinion, whereby longitudinal movement of said head through said housing by said drive pin effects longitudinal and rotational movement of said agitator mill in said ink fountain.

7. An agitator device for the ink fountain of a printing press comprising in combination an elongated housing, a support bracket at each end of said housing for mounting said housing in spaced parallel disposition to

the ink fountain roller of said press, means for clamping said brackets to the frame of said press, means rotatably securing said housing to said brackets for varying the rotational disposition of said housing relative to said roller, an agitator mill in said fountain, a shaft operatively associated at one end with said mill for rotating said mill and travelling said mill longitudinally in said fountain, a mill support head slidably supported in said housing, means rotatably supporting the other end of said shaft in said support head, an endless chain conveyor, a pair of spaced sprockets for mounting said conveyor in said housing for travel therein in a plane generally transverse to said mill shaft, a lateral track formed in said head, a block slidably accommodated in said track, a drive pin on said chain conveyor, rotatably mounted in said block, means for rotating one of said sprockets to travel said conveyor through said housing, said track accommodating lateral movement of said block and pin during reversal of travel of said pin in said housing as it moves around said sprockets with said conveyor, whereby the direction of longitudinal movement of said head in said housing is reversed, and means in said housing for rotating said mill shaft concomitantly with the longitudinal movement of said head in said housing.

8. An agitator device for the ink fountain of a printing press comprising in combination an elongated housing, a support bracket at each end of said housing for mounting said housing in spaced parallel disposition to the ink fountain roller of said press, means for clamping said brackets to the frame of said press, means rotatably securing said housing to said brackets for varying the rotational disposition of said housing relative to said roller, an agitator mill in said fountain, a shaft operatively associated at one end with said mill for rotating said

mill and travelling said mill longitudinally in said fountain, a mill support head slidably supported in said housing, means rotatably supporting the other end of said shaft in said support head, an endless chain conveyor, a pair of spaced sprockets mounting said conveyor for travel in said housing in a plane generally transverse to said mill shaft, means for effecting reciprocation of said head in said housing including a cam pivotally mounted to each side of said head, a drive pin travelling back and forth in said housing on said conveyor, a camming element at each side of said housing positioned in the path of travel of a section of said cams on said head for pivoting the associated cam out of engagement with said drive pin moving in one direction in said housing while simultaneously pivoting the other cam into the return path of

travel of said drive pin in the opposite direction whereby said drive pin alternately engages said cams, pushing said head first in one direction and then in the opposite direction in said housing, and means in said housing for rotating said mill shaft concomitantly with the longitudinal movement of said head in said housing.

9. The invention as defined in claim 8 including a bracket for mounting each of said camming elements on said housing and means for selectively adjusting the position of said brackets on said housing to selectively vary the distance of longitudinal reciprocation of said mill in said fountain.

10. In a rotatable agitator device for the ink fountain of a printing press, the combination comprising an agitator mill, a first shaft rotatably supporting said mill in said fountain, means for rotating said first shaft including a second shaft, a socket means mounting said socket on the end of said first shaft remote from said mill, a locking passage formed in said socket and having an entry section and a locking section therein, a locking element on said second shaft adjacent the end thereof remote from said rotating means and adapted to travel through said passage from said entry section to said locking section for locking said first and second shafts for conjoint rotation.

11. In a rotatable agitator device for the ink fountain

9

of a printing press, the combination comprising an agitator mill, a first shaft rotatably supporting said mill in said fountain, means for rotating said first shaft including a second shaft, means detachably coupling said first and second shafts, and means for rotating said second shaft, second shafts, and means for rotating said second shaft, said coupling means including a socket, means rotatably mounting said socket freely on the end of said first shaft remote from said mill, a locking passage formed in said socket and having an entry section and a locking section therein, a locking element on said second shaft adjacent the end thereof remote from said rotating means and adapted to travel through said passage from said entry section to said locking section upon relative rotation of said socket and said second shaft, and means normally urging said locking element into operative locked position

10
